UNITED STATES PATENT OFFICE.

HENRY FOLTZ, OF SHARON, PENNSYLVANIA.

ANTISLIPPING DEVICE.

1,117,019.

Specification of Letters Patent. Patented Nov. 10, 1914.

Application filed February 1, 1913. Serial No. 745,664.

To all whom it may concern:

Be it known that I, HENRY FOLTZ, a citizen of the United States, residing at Sharon, in the county of Mercer and State 5 of Pennsylvania, have invented new and useful Improvements in Antislipping Devices, of which the following is a specification.

The invention relates to anti-slipping devices and has for an object to provide a device, preferably adapted to be worn on a shoe, to prevent the wearer from slipping on ice or other slippery surfaces.

The invention comprehends, among other 10 features, a simple and durable structure adapted to be attached to the shoe and which includes a series of calks which, when the device is applied to the shoe, project downwardly from the sole to grip into the 20 surface over which a person is walking and prevent the person from slipping or falling.

The device is preferably adapted for use as an ice creeper and may also be employed by athletes to take the place of the usual 25 spiked shoes which they wear to prevent themselves from falling in the participation of athletic events and the like.

The invention still further embodies a device that can be readily adjusted to shoes 30 of different sizes and which will be securely held on the shoe and prevented from slipping or accidentally becoming removed therefrom.

In the further disclosure of the invention 35 reference is to be had to the accompanying drawings, constituting a part of this specification, in which similar characters of reference denote corresponding parts in all the views, and in which:

40 Figure 1 is a perspective view of the device, showing the same applied to a shoe, the shoe being shown in dotted lines; Fig. 2 is a bottom plan view of the device; Fig. 3 is a vertical sectional view taken on the line 45 3—3 in Fig. 2; and Fig. 4 is a vertical sectional view taken on the line 4—4 in Fig. 2.

Referring more particularly to the views, I disclose an anti-slipping device 10, consisting of a plurality of similar, flexible 50 ribbon-like plates 11, pivotally connected at their medial portion by a shank 12 depending from the lowermost plate and provided with an integral reduced shank 13 projecting upwardly through the medial portions 55 of the plates 11, as mentioned, with the upper end of the shank enlarged by flattening

the same so as to pivotally connect the plates 11 and secure the shank 12 in a depending position.

L-shaped clamping members 14, preferably made of the same material as the plates 11, are mounted to swing on the front ends of the plates 11 by calks 15, similar to the shank 12 and adapted to connect the clamping members 14 with the front ends of the plates 11 in the same manner that the plates are pivotally connected at their medial portions, it being thus apparent that the calks 12 and 15 not only perform the function of gripping the anti-slipping members, but 60 also aid in pivotally connecting the plates 11 and mounting the clamping members 14 to swing on the front ends of the plates, it being readily apparent by referring to the views that the calks 15 depend from the 65 under sides of the front ends of the plates 11 in the same manner that the shank 12 depends from the under side of the lowermost plate at the medial portion thereof.

Obviously the clamping members 14 are 70 capable of being swung to different angular positions with relation to the plates 11 so as to automatically adjust themselves to the various curvatures of the soles of the different 75 styles of shoes, when the forward ends of the plates are moved toward each other during the application of the device to the 80 shoe.

A plurality of toe straps 16 are secured to the upwardly extending portions of the 85 clamping members 14 and are preferably connected by a buckle 17 supported on one of the toe straps and adapted to receive the other therethrough so that the toe straps 16 can be relatively adjusted with respect 90 to a shoe 18 disclosed in Fig. 1. Similarly a heel strap 19 is secured to the rear ends of the plates 11, the said heel strap consisting, more particularly, of an elastic section 20 having auxiliary sections 21 made of a 95 strong material attached to the ends of the elastic section and riveted or in any other desirable manner secured to the rear ends of the plates 11.

In the application of the device described 100 to the shoe 18, the toe straps are arranged to pass over the toe end of the shoe so that the plates 11 will lie against the sole of the shoe and the heel strap 19 is then passed around the shoe immediately above the heel 105 thereof, thus exerting a pull on the rear ends of the plates 11 and causing the front ends 110

of the plates to move toward each other, thus resulting in the members 14 exerting a clamping and gripping action on the sole of the shoe adjacent the toe. It will now be 5 apparent that when the device is mounted on the shoe in the manner mentioned that the same will be rigidly held to the shoe and will be prevented from accidentally becoming removed therefrom and it will be further 10 apparent that by having the calks 12 and 15 projecting downwardly from the plates 11 lying against the sole of the shoe, the wearer of the shoe will be prevented from falling or slipping on smooth and slippery 15 surfaces in view of the fact that the calks will dig into the surface and act as creepers.

By providing the buckle 17 connecting the 20 toe straps 16, the device can be adjusted for use on shoes of different sizes and it will be readily seen by referring to the views that the device can be easily attached to and as easily removed from the shoe.

Although the device is preferably adapted 25 for use as an ice creeper, it can also be attached to the shoes of athletes to take the place of the usual spikes secured rigidly in the sole of the shoe.

It will be further noted that by having 30 the plates 11 made of a flexible metal or other material, the plates will readily conform to the curvature of the sole of the shoe to which the device is applied.

Although I have disclosed a particular 35 form of the invention, it will be understood that I do not limit myself to the structure disclosed in the drawings and that various

slight changes may be made without departing from the spirit of the invention, the scope of the invention being defined in the 40 appended claim.

Having thus described my invention, I claim:

In an anti-slipping device for shoes, a pair of crossed pivotally connected plates 45 adapted to be arranged under the sole of the shoe, said plates having their rear ends free of projections so as not to contact with the side of the shoe, calks secured to the underfaces of the plates, an endless strap secured to the rear end of the plates for engagement with the heel of the shoe and adapted to move the forward ends of the said plates toward each other, substantially L-shaped clamping members pivotally secured to the 55 forward ends of said plates for engagement with the sole edges of the shoes, said members being adapted to automatically adjust themselves to the curvature of the sole when said forward ends are moved toward each 60 other; and adjustable front and rear straps connecting said members, said members having that portion that engages the sole of the shoe converging toward each other so as to prevent displacement of said plates downwardly independent of said front adjustable strap.

In testimony whereof I affix my signature in presence of two witnesses.

HENRY FOLTZ.
